US00D969535S

(12) **United States Design Patent** (10) Patent No.: **US D969,535 S**
Tu (45) Date of Patent: **** Nov. 15, 2022**

(54) **BLENDER BASE**

- (71) Applicant: **SHARKNINJA OPERATING LLC**, Needham, MA (US)
(72) Inventor: **Joyce Chien Tu**, Melrose, MA (US)
(73) Assignee: **SHARKNINJA OPERATING LLC**, Needham, MA (US)
(**) Term: **15 Years**

(21) Appl. No.: **29/824,701**

(22) Filed: **Jan. 26, 2022**

Related U.S. Application Data

- (63) Continuation of application No. 29/766,283, filed on Jan. 14, 2021, now abandoned, which is a continuation of application No. 29/743,230, filed on Jul. 20, 2020, now Pat. No. Des. 938,220.

(57) **CLAIM**

The ornamental design for a blender base, as shown and described.

DESCRIPTION

FIG. 1 is a perspective view of a blender base showing my new design;

FIG. 2 is a front view of the embodiment shown in FIG. 1; FIG. 3 is a rear view of the embodiment shown in FIG. 1; FIG. 4 is a side view of the embodiment shown in FIG. 1; FIG. 5 is another side view of the embodiment shown in FIG. 1;

FIG. 6 is a top view of the embodiment shown in FIG. 1; and,

FIG. 7 is a bottom view of the embodiment shown in FIG. 1.

The broken lines in the drawings are for environmental purposes only and form no part of the claimed design.

1 Claim, 5 Drawing Sheets
